UNITED STATES PATENT OFFICE.

GEORGE S. KING, OF BAY SHORE, NEW YORK.

HEATER FOR AUTOMOBILES.

1,363,880.

Specification of Letters Patent. Patented Dec. 28, 1920.

Application filed December 16, 1919. Serial No. 345,251.

To all whom it may concern:

Be it known that I, GEORGE S. KING, a citizen of the United States, and a resident of Bay Shore, in the county of Suffolk and State of New York, have invented new and Improved Heaters for Automobiles, of which the following is a full, clear, and exact description.

The object of the invention is to provide a new and improved heater for automobiles and other power driven vehicles located within the hood adjacent the internal combustion engine to heat the latter with a view to prevent the water of the cooling system from freezing and to keep the heater and connected parts in proper condition for readily starting the motor whenever it is desired to do so.

Another object is to enable the operator in charge of the automobile to readily light the heater.

Another object is to provide a heater that can be safely used.

Another object is to require no attention on the part of the operator to start the heater from the dashboard and without opening the hood.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in both views.

Figure 1 is a side elevation partly in section of the front end of an automobile provided with the improved heater; and

Fig. 2 is an enlarged sectional side elevation of the heater.

The heater 10 for heating the internal combustion engine 11 of an automobile 12 is arranged within the hood 13, and the heater is preferably in the form of a safety lamp of the Davy or similar type. The lamp comprises a casing 15 provided at the bottom with an air inlet screen 16 and having at the top a chimney 17 above which is arranged a conical hood or deflector 18 for deflecting the products of combustion downwardly outside of the chimney 17 and into a chamber having its side wall formed of an inverted conical screen 19 attached at its small end to the top of the casing 15. The

upper end of the screen 19 supports the hood 18.

Within the casing 15 is arranged a burner, preferably in the form of an annular wick holder 20 closed at the bottom and adapted to contain a cylindrical wick 21. The lower end of the wick holder 20 is provided with a tube 22 screwing on the inner end of a boss 23 formed on one side of the casing 15. The outer end of the boss 23 is connected with one end of a supply pipe 24 provided with a shut-off valve 25 and connected with the float chamber of a carbureter 26 of the internal combustion engine 11. The carbureter 26 is connected by the usual supply pipe 27 with the gasoline tank of the automobile for supplying gasoline or other liquid fuel to the carbureter 26. The heater 10 is arranged in such relation to carbureter 27 that the level of the liquid fuel within the float chamber of the carbureter 27 is about midway of the height of the wick holder 20, as indicated by the dotted line in Fig. 2. By the arrangement described the wick 21 is charged with gasoline from the gasoline supply of the internal combustion engine 11 and an overflow of gasoline in the wick holder 20 is prevented.

In order to light the lamp, use is made of a spark plug 30 of any approved construction and screwing in a boss 31 of the casing 15. The spark gap 32 of the spark plug 30 is arranged adjacent the upper end of the wick holder 20 so as to light the lamp whenever it is desired to use the heater. The spark plug 30 is connected by a wire 35 connected with the electric ignition system of the internal combustion engine 11, and the said wire 35 is provided with a switch 36, preferably located at the dashboard to be within convenient reach of the operator in charge of the automobile. It will be noticed that when the switch 36 is closed electrical energy passes to the spark plug 30 with a view to produce a spark at the gap 32 to ignite the wick 21 of the burner. From the foregoing it will be seen that by the arrangement described the liquid fuel for the heater is derived from the liquid fuel supply of the internal combustion engine 11 and the lighting means for the burner of the heater are derived from the electric ignition system of the internal combustion engine.

It will further be noticed that the safety lamp which forms the heater is not liable to set the automobile on fire,

It will further be noticed that by arranging the heater in heating relation to the internal combustion engine 11, the cooling system of the latter is not liable to freeze 5 in severe winter weather and at the same time the internal combustion engine is kept in proper condition for readily starting the automobile whenever it is desired to do so.

It is understood that after the lamp is 10 lighted, the switch 36 is opened to shut off the supply of electrical energy to the spark plug 30.

Having thus described my invention, I claim as new and desire to secure by Letters Patent:—

1. In a power driven vehicle having an internal combustion engine as the motive power, a wick lamp engine heater deriving its fuel from the fuel supply of the engine 20 and arranged in heating relation to the engine, and a lighting device for the heater connected with the ignition system of the engine.

2. In a power driven vehicle having an internal combustion engine as the motive power, a wick safety lamp arranged in heating relation to the engine and deriving its fuel from the fuel supply of the engine, and an electric lighting device for lighting 30 the lamp and connected with the ignition system of the engine.

3. In a vehicle having an internal combustion engine as the motive power, a heater comprising a wick lamp and connected with 35 the fuel supply of the engine, the heater being arranged in heating relation to the engine, and an electric lighting device connected with the ignition system of the engine and with the said heater to light the 40 lamp.

4. In a power driven vehicle having an internal combustion engine as the motive power, a wick safety lamp arranged within the hood of the engine and arranged in 45 heating relation to the engine, the said lamp being provided with a burner approximately on the level of the carburetor of the engine, a connection between the burner and the fuel supply of the engine to supply 50 the burner with liquid fuel, and an electric lighting device for the lamp connected with the ignition system of the engine.

5. In a power driven vehicle having an internal combustion engine as the motive 55 power, a safety lamp arranged adjacent the engine and having a lamp casing provided

with safety screens, a wick holder within the casing, a supply pipe connected with the said wick holder to supply the latter with liquid fuel, and a spark plug having its 60 spark gap at the wick holder to light the wick.

6. In a power driven vehicle having an internal combustion engine as the motive power, a safety lamp in heating relation 65 with the engine, and comprising a lamp casing having a screen inlet at the bottom and a screen outlet at the top, a wick holder arranged in the casing and adapted to contain a wick, a fuel supply pipe attached to the casing and connected with the said wick holder to supply the latter with liquid fuel, and a spark plug attached to the said lamp casing and having its spark gap adjacent 70 the wick holder to light the lamp.

7. In a power driven vehicle having an internal combustion engine, a lamp arranged in heating relation with the said engine and comprising a casing provided at the bottom with a screen for the entrance 80 of the air, a chimney on the top of the casing, a hood for the chimney, a screen surrounding the chimney and supporting the said hood, and a burner within the casing below the chimney.

8. In a power driven vehicle having an internal combustion engine, a lamp arranged in heating relation with the said engine and comprising a casing provided at the bottom with a screen for the entrance of 90 the air, a chimney on the top of the casing, a hood for the chimney, a screen surrounding the chimney and supporting the said hood, and an annular wick holder supported within the casing centrally below the 95 chimney.

9. In a power driven vehicle having an internal combustion engine, a lamp arranged in heating relation with the said engine and comprising a casing provided at 100 the bottom with a screen for the entrance of the air, a chimney on the top of the casing, a hood for the chimney, a screen surrounding the chimney and supporting the said hood, an annular wick holder supported within 105 the casing centrally below the chimney and having a tube attached to the casing, a supply pipe connected with the said tube, and a spark plug secured to the casing and having its spark gap arranged adjacent the top 110 of the said wick holder.

GEORGE S. KING.
